AMPHIBIAN AIRCRAFT

Anthony Toth, Inglewood, Calif.

Application March 28, 1955, Serial No. 35,244

Term of patent 14 years

(Cl. D71—1)

FIG. 1.

FIG. 2.

Fig. 4.

Fig. 1 is a perspective view taken from the front and one side of an amphibian aircraft embodying my new design. Fig. 2 is a perspective view of the design shown in Fig. 1, taken from the rear and other side. Fig. 3 is a top plan, and Fig. 4 is a front elevation thereof.

The essential features of my design reside in the portions shown in full lines.

I claim:

The ornamental design for an amphibian aircraft, as shown and described.
